UNITED STATES PATENT OFFICE.

RICHARD METCALF, OF DAYTON, OHIO, ASSIGNOR TO THE BROWNELL & COMPANY, OF SAME PLACE.

DESIGN FOR A SIDE HANGER FOR STEAM-BOILERS.

SPECIFICATION forming part of Design No. 31,868, dated November 21, 1899.

Application filed October 30, 1899. Serial No. 736,323. Term of patent 14 years.

To all whom it may concern:

Be it known that I, RICHARD METCALF, a citizen of the United States, residing at Dayton, in the county of Montgomery and State 5 of Ohio, have invented and produced a new and original Design for a Side Hanger for Steam-Boilers; and I do declare the following to be a full, clear, and exact description of the same, reference being had to the accompanying drawings, forming a part thereof.

Figure 1 is a front view of a side hanger for steam-boilers, the same showing my new design. Fig. 2 is a sectional view of the hanger on the line $x-x$ of Fig. 1, looking in either direction.

As shown in the drawings, the leading or material feature of my design consists of two parallel plates or flanges A and B, which are provided with rivet-holes, and a top tubular 20 portion C, which is curved and an integral part of the flanges A and B. The said curved

tubular portion C forms an eye D. The flanges or plates A and B have the curvature or concavo-convex form shown in Fig. 2, which causes the lower ends of said flanges to lie in a vertical plane on one side of the tubular portion C. As shown in Fig. 1, the tubular portion C joins the upper ends of the flanges or plates A and B at a point in line with the longitudinal centers of said flanges. 25

Having described my invention, what I claim, and desire to secure by Letters Patent, is—

The design for a side hanger for steam-boilers, as herein shown and described. 30

In testimony whereof I affix my signature in presence of two witnesses.

RICHARD METCALF.

Witnesses:

JOHN W. KALBFUS,
R. J. McCARTY.
